UNITED STATES PATENT OFFICE.

JOSEPH H. F. LAFLAMME AND OMER GRAVEL, OF TORONTO, ONTARIO, CANADA.

BOMB-DROPPER.

1,231,387.

Specification of Letters Patent. Patented June 26, 1917.

Application filed April 4, 1916. Serial No. 88,881.

To all whom it may concern:

Be it known that we, JOSEPH H. F. LAFLAMME and OMER GRAVEL, subjects of the King of Great Britain, residing at Toronto, in the Province of Ontario and Dominion of Canada, have invented certain new and useful Improvements in Bomb-Droppers, of which the following is a specification.

This invention has relation to bomb dropping devices, and the nature and objects thereof will be readily apparent to those skilled in the art in the light of the following explanation, of the accompanying drawings, illustrating what we now believe to be, the preferred embodiment, or mechanical expression of our invention, from among other forms within the spirit of the invention, and the scope of the appended claims.

However, an object of the invention is to provide a bomb dropping device for aeroplanes whereby the necessity for an operator for the device is obviated, and means provided for enabling the driver of the aeroplane to release the bombs at the proper time, without interfering in any manner whatsoever with the operations incidental to the control of the aeroplane.

Another object of the invention is to provide a bomb dropping device for aeroplanes to be used in connection with the type of bombs at present employed by the French Government, and means for carrying a plurality of said bombs, and for releasing the bombs one at a time, and in consecutive order.

Another object of the invention is to provide in a device of the character described means for preventing mutual contact of adjacent bombs so as to preclude premature explosion thereof.

In addition to the foregoing our invention comprehends improvements in the details of constructions and arrangement of parts, to be hereinafter described, and particularly pointed out in the appended claims.

In the accompanying drawings in which similar and corresponding parts are designated by the same characters of reference throughout the several views in which they appear,

Figure 1, is a view in side elevation of a conventional type of aeroplane illustrating the application of our invention.

Fig. 2, is an enlarged view in side elevation of a bomb dropping device constructed after the manner of our invention.

Fig. 3, is an end elevation thereof.

Fig. 4, is a plan view of the device.

Fig. 5, is a transverse section.

Fig. 6, is a transverse section through the mechanism for producing intermittent motion of the tripping chain, and

Fig. 7, is a vertical section on the line 7—7 of Fig. 6.

While it is our object, to design the invention for use in connection with a particular type of aerial-bomb it will be apparent as the description proceeds that the device may be altered for use in connection with different types of bombs. In devices of this kind heretofore known to ourselves, no provision was made for carrying a comparatively large number of bombs at one time, nor for disposing all of them at once so as to be instantly available for discharge. Furthermore in devices of this character heretofore provided, the services of an operator was necessary therefor, thus entailing an additional weight in addition to the aeroplane operator, and the loss of two lives in the event that mishap should overtake the machine in its flight.

Proceeding with the description of the device, 1 designates an aeroplane having longitudinal frame members 2 connected by transverse members 3. A main frame member 4 is provided which is substantially triangular in cross section with the apex thereof extended downwardly. This frame member 4 may be made of any length desired, but has been illustrated in this instance as extending from the front of the aeroplane rearwardly to a point coincident with the rear edges of the supporting planes.

Platforms 5 and 6 are formed at the front and rear terminals of the frame 4 for supporting bearing brackets 7 and 8 respectively. The front bracket 7 is formed with a transversely extending casing 9, the ends of which are centrally apertured, one end thereof 10 being in the form of a removable cap. A sprocket wheel 11 is provided with a sleeve 12 which extends through the aperture in one end of the casing and has rigidly mounted thereon in the interior of the casing, a ratchet wheel 13; a shaft 14 is mounted within the sleeve 12 and after pass-

ing through the casing and the removable head is secured against displacement by the application of nuts 15 upon its reduced threaded extremity 16. An arm 17 is 5 formed on the opposite terminal of the shaft 14 and is provided with a shoulder 18 for engagement against the sprocket 11. A disk 19 is secured for rotation therewith, and upon the shaft 14 in the interior of the 10 casing 9, and contiguously disposed with relation to the ratchet wheel 13. Pawls 20 are mounted for engagement with the ratchet wheel and are resiliently retained in such engagement by leaf springs 21.

15 The rear bracket 8 is formed on either side with a longitudinal slot for the reception of bearing blocks which support the shaft 22 of a sprocket 23. Threaded elements are mounted in said bracket and engage opposite 20 sides of the bearing block, whereby said bearing block, the shaft journaled therein, and consequently the sprocket 23 may be horizontally reciprocated.

An endless chain 24 is disposed between 25 the sprocket wheels 11 and 23, so that its upper stretch is disposed centrally and above the frame 4 and movable within a longitudinal recess 25 in the upper surface of the frame. The lower stretch of said 30 chain may travel beneath the frame in the manner illustrated. A tripping block 26, substantially wedge-shaped, is mounted on the outer surface of the chain for a purpose which will presently be apparent.

35 Formed upon the upper surface of the main frame are intermediate, spaced, longitudinally extending ribs or the like 27, and side rails 28. The side rails 28, and the intermediate ribs 27 are provided in staggered 40 relation with pairs of transversely extending apertures in which are mounted for sliding movement pins 29 having inwardly extending apertured extremities 30. Bell cranks 31 are pivotally mounted upon the upper surface of the main frame with one of 45 their arms extending transversely across the chain 24 in the path of movement of the lug 26, and their other arms connected by means of links 32 to the inner extremities 50 of the pins 29. Vertical recesses are formed in the side rails to intersect the transverse recesses therein as at 33.

The bombs 34 are provided with directing 55 devices 35 and apertured lugs 36 which are adapted to be seated within the vertical recesses of the side rails 28 so as to be secured therein by the pins 29 which pass through the recesses of said lugs, and thereby support the bombs. Spherical members 37 60 which may be composed of rubber, or other resilient material are supported upon depending arms 38 for disposition between adjacent bombs. In this manner contact between adjacent bombs is precluded and prevents 65 mature explosion of the bombs, which might

result from such contact is absolutely avoided.

A foot lever 39 is pivoted at 40, and has its lower extremity connected by means of a rod 41 to the upper extremity of the arm 17. 70 Curved brackets 42 are mounted in close relation to the lever 39 and are provided with adjustable stops 43 for engagement by said lever to limit its movement in either direction.

In operation, and before the aeroplane is to take flight the desired number of bombs are suspended upon the rods 29 and the chain 24 so disposed that the lug 26 thereof is located at the front of the frame and in 80 proximity to the bell crank arm of the first bomb releasing mechanism. During the flight of the machine should the operator thereof desire to release a bomb, he presses upon the lever 39, and owing to the connection therewith of the arm 17, said arm through its movement rotates the shaft 14, disk 19, ratchet wheel 13, sprocket wheel 11, and the upper stretch of the chain is moved sufficiently to cause engagement between the 90 bell crank 31, and the lug 26, whereby the rod 29 is withdrawn from the aperture in the lug 36, and the bomb thereupon released. When the lever 39 is released, and is returned under the influence of the spring 95 44, the arm 17 is returned to its former position; the mechanism is thus reset for a second actuation, and upon said actuation the lug 26 is moved into position for engaging the second bomb releasing means at 100 the opposite side of the frame.

While we have illustrated a design of our invention wherein one bomb is releasable at a time, and wherein the bombs are disposed at opposite sides of the frame, it will be obvious that the bombs may be arranged in alignment, or may be made releasable simultaneously if desired. Various ways of constructing our invention will occur to those skilled in the art, and we therefore reserve 105 the right and privilege of changing the form of the details, and otherwise altering the arrangement of parts without departing from the spirit of the invention or the scope of the appended claims.

Having thus described our invention what we claim and desire to secure by Letters Patent is:—

1. A bomb dropping device including a frame, a plurality of releasable bomb suspending means disposed at opposite sides of the center of the frame, a chain movable centrally of the frame, sprocket wheels at each end of the frame around which the chain passes, a ratchet wheel movable with 12 one sprocket wheel, a shaft for loosely supporting the said sprocket wheel and ratchet wheel, a disk secured to the shaft, spring pressed pawls on the disk for engaging the ratchet, an arm on the shaft, means con- 13

nected to the arm for oscillation thereof whereby the chain may be moved intermittently, and in one direction, and means on the chain for successively engaging the suspending means for releasing the bombs.

2. A bomb dropping device including a longitudinal frame, a plurality of releasable bomb suspending means at opposite sides of the frame, sprocket wheels at the forward and rear end of the frame, a chain passing around the sprocket wheels and movable centrally of the frame, means on one sprocket wheel for varying tension of the chain, means on the chain for engaging the suspending means individually and in order, to release the bombs, a shaft for loosely supporting the other sprocket wheel, a sleeve integral with said sprocket wheel and surrounding the shaft, a casing in which the sleeve and shaft are rotatably mounted, sprocket wheel being exteriorly disposed to the casing, a ratchet wheel fixed to the sleeve and disposed interiorly of the casing, a disk secured to the shaft within the casing, spring pressed pawls mounted on the disk for engagement with the ratchet wheel, an arm fixed to one terminal of the shaft, and means for oscillating the arm whereby the

chain may be moved intermittently and in one direction.

3. The combination with an aeroplane of a bomb dropping device including a frame, a plurality of releasable bomb suspending means, a flexible element movable along the frame, means on the flexible element for actuating during movement the bomb suspending means, individually and in order, means for imparting an intermittent motion to the flexible element and in one direction, a rod connected to said means, a foot lever connected to the rod and within reach of the aeroplane operator, brackets at either side of the lever and in the path of movement thereof, and movable stops on the brackets engageable by the lever to limit the movement thereof, whereby the degree of movement of the flexible element may be varied.

In testimony whereof we affix our signatures in presence of two witnesses.
